AIR COMPRESSOR

Sellers E. Jessup, Los Angeles, Calif.

Application May 26, 1941, Serial No. 395,162

5 Claims. (Cl. 238—231)

My invention relates to improvements in air compressors and more particularly to that class of fluid compressors which is generally although not exclusively employed for compressing air, gas and other fluids in the various arts. While it is desirable to reduce the initial cost of construction as much as possible consistent with strength, durability and effectiveness, it is a major object of the invention to produce a maximum of fluid pressure with a minimum of power, thus tending toward greater economy and saving in expense of operation. Still further objects are greater efficiency, durability and simplicity. To these ends my invention comprises the features of construction and combination of parts hereinafter described and claimed.

In the drawings forming part of this specification, Fig. 1 is a vertical central section of my improved fluid compressor which is of reciprocable piston and cylinder type, the piston being shown as it approaches fully fluid compression position near the inner end of its compression stroke, the broken line position indicating the outermost position assumed by the piston and its actuated return check valve removed from the compressor; Fig. 3 is a top plan of the fluid actuated return valve shown in Fig. 2, part of the structure being broken away and in section showing the fluid ingress port openings; Fig. 4 is a bottom plan of the structure shown in Fig. 2; Fig. 5 is a transverse vertical section taken on the line 5—5 of Fig. 1; Fig. 6 is a transverse horizontal section taken on line 6—6 of Fig. 5; Fig. 7 is a diagram illustrating the increased ratio of exhaust during the compression stroke, and Fig. 8 is a vertical central section of an alternate construction of the upper end of the return check valve portion of my improved compressor.

In the drawings A indicates the cylinder, B the piston which is reciprocable in said cylinder, and C the crank case, of my improved compressor. 10 is a suitable crank shaft journaled in the horizontal sleeve 11 extending laterally from the crank case, and having a suitable driving element such as pulley 12 on its outer end and a crank 13 on its inner end. A suitable pitman or connecting rod 14 is connected to the crank. A toggle D composed of lower and upper arms 15 and 16 flexed together by the pintle 17 is connected by said pintle to the free end of the pitman. The lower extremity of the lower arm 15 of the toggle is journaled to rock by the bearing 18 on the lower portion of the crank case and the upper extremity of the upper arm 16

is journaled by the piston pin 19 in the piston B. As the crank is revolved in the direction of the arrow shown in Fig. 1, the piston and the toggle are reciprocated from the full line position as the piston approaches fully compressed position to the broken line position at the lower end of the fluid intake stroke, as shown in Fig. 1.

The cylinder is extended upwardly and increased in diameter to provide a cylindrical valve chamber E, the latter being closed by an end cover plate 20. A return check valve of float piston type F reciprocable coaxially with and of greater diameter than the diameter of piston B in the cylindrical valve chamber closes downwardly upon the annular outwardly flaring seat 21, the latter being arranged at the junction between the compression cylinder and the wall of the valve chamber above and connecting with an annular outlet channel 42 adjacent thereto 10 in the wall of the cylindrical casing. The return check valve F resembles a piston having a hollow cylindrical casing 22 closed at its upper end by the horizontal end wall 23 and provided with fluid ingress ports 24 in its side wall and a valve closed horizontal lower end wall 25. The ports 24 are adapted to register with fluid ingress openings such as 26 in the side wall of the valve chamber. The lower end wall of the fluid return check valve has a comparatively large annular fluid inlet centrally disposed and surrounded by a valve seat or orifice 27 with which an annular fluid admission check valve 28 closes automatically to seal the passage through the fluid return check valve F during the compression stroke of piston B. A compressed fluid outlet port 30 from the annular outlet channel 42, through the wall of the cylinder, leads outwardly for transmitting the fluid which is compressed by piston B. Sealing rings 31 seated in the 15 cylindrical surface of the return check valve F and a sealing cup 32 made out of lead or other suitable material in the return check valve cylinder are provided to maintain a tight working connection between the return check valve F and said cylinder. By making valve F larger in diameter than the main cylinder of the compressor a comparatively large valve area is provided whereby a very slight reciprocable opening and closing movement is necessary for discharging the compressed fluid and closing the valve. In practice a compressor employing a fluid compressing cylinder of 6" internal diameter has required less than a $\frac{1}{2}$ inch opening movement. The fluid admission check valve 28 in the return 20 check valve F has a central valve stem 33 which

reciprocates freely in a bridge support 36 integral with the side wall of the cylindrical float return check valve structure. A helical spring 37 fitted over the body of the bridge support and below a washer 38 tends to hold the inner fluid ingress check valve 28 contained in the return check valve closed but permits it to open freely during the intake stroke of piston B. Thus during the intake stroke, the fluid medium to be compressed is drawn through the openings 26, ports 24 and the valved orifice 27 in the return check valve F into the compression chamber within cylinder A. During this action the return check valve closes and is held closed automatically upon its seat thus checking any return of compressed fluid from duct 39. This closing action of the return check valve is produced partly by the negative pressure or suction created by the intake stroke of piston B but mainly by the pressure exerted by compressed fluid previously admitted either by duct 40, or external duct 41, or both, into the return check valve chamber above valve F therein. Duct 40 leads upwardly from the circular fluid outlet channel 42 (see Fig. 6) through the side wall of and into the cylindrical chamber above the return check valve F and duct 41 is connected with outlet duct 39 and leads through cover plate 20 into said chamber, a suitable check valve 43 being interposed to prevent return of compressed fluid previously admitted. In the manner stated the return float check valve F is held firmly closed except when fluid is compressed under sufficient pressure by the compression piston B to overcome the automatic closing tendency of the return check valve.

Normally the lower flat surface of fluid admission check valve 28 lies on the plane of the lower end flat surface of the return check valve F and substantially no clearance space is allowed between the piston and lower surface of the return check valve at the upper end of the stroke of the compression piston B, whereby substantially all of the compressed fluid and heat of compression is expelled and conducted away from the compression chamber during each compression stroke of the apparatus. During compression the opening movement of the return check valve is cushioned by the pressure of compressed fluid above the return check valve and the return check valve is quickly closed upon the piston reversing to the intake stroke. The larger effective area of the return check valve over that of the compression piston increases the closing force imparted by the fluid upon the valve. Due to the relatively large ingress and egress valve areas provided, very slight movement is required to move the return check valve into wide open position for the egress of compressed fluid and heat of compression, or into closed position for the compression of fluid during the compression stroke. During operation the crank case provides a convenient reservoir for lubrication liquid by which the bearings of the various parts are kept lubricated.

My improved structure produces complete exhaust of the compressed fluid and the heat of compression, resulting in increased efficiency and more economical operation. It avoids the necessity of using multiple stage cylinders for obtaining the desired volumetric compression and reduces the power required for operation. The check valve F of reciprocable piston type, closed and cushioned by the increased pressure resulting from the compressed fluid, provides a positive and quick acting check which prevents the return of any previously compressed fluid into the com-

pression chamber and produces smooth, efficient and economical operation in a simple and effective manner. The toggle drive for reciprocating the compression piston in cooperation with the valve control described produces increased efficiency due principally although not exclusively to the lengthened compression stroke, the increased period of exhaust and the comparatively short period during which fluid is admitted by the intake valve into the compression chamber. As indicated in the diagram appearing in Fig. 7, the toggle lengthens the compression stroke to approximately 200 degrees during which the exhaust period is prolonged, thus allowing substantially all of the compressed fluid to be expelled. Thus the check valve F coordinates with the toggle in producing improved results. This increased ratio in compression and exhaust is produced by arranging the axis of the crank in horizontal alignment with the upper end of the bottom link when said link and the compression piston are in lowermost position as shown in the diagram. From the diagram it will be noted that when the link and piston revolve from lowermost to uppermost position the connection between the connecting rod and toggle moves through about 200 degrees of the arc through which the crank travels. In this manner the compression stroke and the exhaust period are increased which is a distinct advantage. Also the radius (of about 169 degrees) during the period of intake is materially reduced leaving a longer period for compression. During the prolonged exhaust, the power applied to the crank is materially reduced by the use of the toggle over that provided by a simple crank without a toggle.

In Fig. 8, the cylinder A is shown increased in diameter at its upper end 59 above the return check valve F and the packing cup 51 enlarged to provide in effect a supplemental piston of increased area acting against the return check valve F to close the latter more effectively by the increased force supplied by the compressed fluid.

In accordance with the patent statutes, I have described the principles of operation of my invention together with the construction which I now consider to represent the best embodiment thereof, but I desire to have it understood that the structure shown is only illustrative and that the invention can be carried out by other means and applied to uses other than those above set forth within the scope of the following claims.

I claim:

1. A fluid compressor having a cylinder forming a compression chamber, a piston reciprocable in said compression chamber, said cylinder having a return check valve chamber of increased diameter and provided with an annular valve seat between said compression and valve chambers, and an outlet duct for compressed fluid from said valve seat, a piston return check valve reciprocable in said valve chamber in cooperation with said seat controlling the return of compressed fluid into the compression chamber, said piston return check valve having an intake duct through the wall of said cylinder entering the compression chamber for fluid to be compressed, an intake check valve controlling the fluid entering the compression chamber through said return check valve, said return check valve chamber having a connection with said outlet duct by which compressed fluid is admitted into said valve chamber above the return check valve tending to close said return check valve upon said seat, and a check in said last mentioned connection for pre-

venting the return of compressed fluid admitted into said valve chamber.

2. A fluid compressor having a cylinder forming a compression chamber, a piston reciprocable in said compression chamber, said cylinder having an extension of increased diameter beyond the compression chamber provided with an annular valve seat at its junction with said compression chamber having an outlet for compressed fluid, a return check valve reciprocable in said valve chamber, and adapted to close upon said seat, a connection for compressed fluid from the compression chamber controlled by said return check valve and entering said return check valve chamber whereby fluid compressed by the compression piston is adapted to urge the return check valve upon its seat, the adjacent surfaces between the compression piston and said return check valve being arranged substantially without clearance at the upper end of the compression stroke of the compression piston, said return check valve having an intake duct through the wall of the cylinder and entering said compression chamber, an intake check valve in said duct maintained closed by compressed fluid in said compression chamber and opened by negative pressure of fluid created by the intake stroke of said compression piston, and a sealing cup above the return check valve in said valve chamber for maintaining a tight working connection between the return check valve and the wall of the valve chamber.

3. A fluid compressor having a cylinder forming a compression chamber, a piston reciprocable in said compression chamber, said cylinder having a return check valve chamber provided with an annular seat adjacent to said compression chamber, a return check valve reciprocable in said valve chamber and adapted to close upon said seat, an outlet connection for compressed fluid from the compression chamber controlled by said return check valve and entering said return check valve chamber above said return check valve whereby fluid compressed by said reciprocable piston is adapted to urge the return check valve upon its seat, a check in said outlet connection for preventing return of compressed fluid admitted into said valve chamber, the adjacent surfaces between the compression piston and said return check valve being arranged substantially without clearance at the upper end of the compression stroke of said piston, and said return check valve having a valved intake duct for the

admission of fluid into said compression chamber, said duct being maintained closed by compressed fluid in said compression chamber and opened by negative pressure of fluid created by the intake stroke of said compression piston.

4. A fluid compressor having a cylinder forming a compression chamber, a piston reciprocable in said compression chamber, said cylinder having a return check valve chamber and an annular valve seat adjacent to said compression chamber, a hollow return check valve reciprocable in said valve chamber and adapted to close upon said seat, an outlet connection for compressed fluid from the compression chamber controlled by said return check valve and entering said return check valve chamber above said return check valve whereby fluid compressed by said reciprocable piston is adapted to urge the return check valve upon its seat to close said outlet connection, a check in said outlet connection for preventing the return of compressed fluid admitted into said valve chamber, and said return check valve having a valved intake duct for the admission of fluid into said compression chamber, the valve in said duct being maintained closed by compressed fluid in said compression chamber and opened by negative pressure of fluid created by the intake stroke of said compression piston.

5. A fluid compressor having a cylinder forming a compression chamber, a piston reciprocable in said compression chamber, said cylinder having a return check valve chamber provided with an annular seat adjacent to said compression chamber, a return check valve reciprocable in said valve chamber and adapted to close upon said seat, an outlet connection for compressed fluid from the compression chamber controlled by said return check valve and entering said return check valve chamber above said return check valve whereby fluid compressed by said reciprocable piston is adapted to urge the return check valve upon its seat, a check in said outlet connection for preventing return of compressed fluid admitted into said valve chamber, and said return check valve having a valved intake duct through the wall of the cylinder for the admission of fluid into said compression chamber, said duct being maintained closed by compressed fluid in said compression chamber and opened by negative pressure of fluid created by the intake stroke of said compression piston.
